WIJTSE BEIJE SMITS, OF DILMEN, NETHERLANDS.

ELECTRIC HEATING APPARATUS.

1,414,226.

Specification of Letters Patent. Patented Apr. 25, 1922.

Application filed March 1, 1920. Serial No. 362,516.

To all whom it may concern:

Be it known that I, WIJTSE BEIJE SMITS, subject of the Netherlands, and resident of Dilmen, Netherlands, have invented certain 5 new and useful Improvements in Electric Heating Apparatus, of which the following is a specification.

Electric heating bodies are already known that are composed of a heat-refractory insulating body for receiving the resistances, and of a metal casing which encloses the whole and which is formed by casting metal around the insulating body.

Heating bodies of that kind have however 15 a low efficiency because the insulating body hinders very considerably the radiation of the heat. Moreover the material cast around the heating elements has a lower co-efficient of expansion than the inner core. Since the 20 core is far more heated by the intermediate insulating body than the casing, the entire heating body is liable to burst asunder. Also, after use, owing to the more rapid cooling of the cast material, stresses are produced 25 which may result in the destruction of the apparatus.

The present invention consists in improvements in such apparatus whereby the heat can pass more readily from the resistance 30 elements to the parts or objects that are being heated, the liability of destruction due to the relative co-efficients of expansion and rates of cooling of the core and casing is practically eliminated, and access of the 35 oxygen to the heating elements is effectively prevented.

For this purpose according to my invention the heating elements are arranged alternately with the clamping plates, in a metal 40 casing in which they can be fixed for instance by means of wedges. The core thus produced is enclosed in a casing which is cast around it and which is formed of a material which is a good heat conductor 45 and which has a higher coefficient of expansion than that of the material of which the clamping plates are composed.

If the clamping plates and the casing are made for instance of copper, then aluminium 50 for example may be used as the surrounding material. In cooling, the aluminium

shrinks to a greater extent than the copper and thus presses the heating cores very tightly together.

In the accompanying drawing, Figure 1 55 is a section in line *c-d* of Figure 2 of one embodiment of my invention and Figure 2 is a section on line *a-b* of Figure 1.

In the drawings, numeral 1 indicates the plates of copper for instance, which are 60 wedge shaped at their ends, while 2 indicates the resistance elements. The latter are preferably of wire between mica plates. The alternate plates and elements are held in alinement by bolts 3. The whole is surrounded by the aluminum case indicated at 4.

The current conducting wires are diagrammatically shown in Figure 2.

By varying the shape of the cores an 70 apparatus constructed in this manner can be used for very different purposes. When made in block shape it can be employed as a dipping apparatus, or in combination with a copper body as a soldering bit. In the 75 form of a plate it can be used as the bottom of a boiler.

In this manner also it is possible to cast resistance wires which are provided for instance with a coating of enamel, directly in 80 the form of rods or bars which can be used as curling tongs, medical instruments, electric furnaces and the like. The electric insulating material is protected on all sides by the surrounding material, thus preventing 85 the possibility of the enamel coating breaking.

The main advantages of the improved heating apparatus made in this manner are the following:

1. The complete exclusion of oxygen, whereby great durability is ensured even under a very high load;
2. Direct contact with the covering, that is to say, a good transfer of the heat;
3. Watertightness, and consequently the prevention of short-circuiting due to moisture;
4. Great mechanical strength, especially when dropped, because nothing can become 100 loose inside the apparatus.

Having now particularly described and

ascertained the nature of my said invention and in what manner the same is to be performed, I declare that what I claim is:—

An electric heater, comprising a core composed of resistance elements and clamping plates arranged in alternation, and a coating of heat-conducting material enclosing said core, said heat-conducting material having a higher coefficient of expansion than the

material of which the clamping plates are constructed.

Signed at Amsterdam, Netherlands, this 6th day of February, 1920.

WIJTSE BEIJE SMITS.
